UNITED STATES PATENT OFFICE.

WILLIAM M. CALKINS, OF SYRACUSE, NEW YORK.

APPARATUS FOR MIXING LIQUIDS.

1,420,079.

Specification of Letters Patent. Patented June 20, 1922.

Application filed February 3, 1920. Serial No. 356,084.

To all whom it may concern:

Be it known that I, WILLIAM M. CALKINS, of Syracuse, in the county of Onondaga, in the State of New York, have invented new and useful Improvements in Apparatus for Mixing Liquids, of which the following, taken in connection with the accompanying drawings, is a full, clear, and exact description.

10 This invention relates to certain improvements in apparatus for mixing liquids, such as various soda beverages and other miscible substances and refers more particularly to that type in which the agitator is driven by 15 an electric motor.

One of the objects is to mount the agitator directly upon the shaft of a vertically reciprocating motor capable of being easily and quickly displaced by hand against the 20 action of suitable retracting springs to bring the agitator into the receptacle containing the liquid to be mixed and automatically locking the same in its operative position so that the mixing operation may proceed 25 without further attention from the operator until the mixing is completed, whereupon the motor may be easily and quickly released by the operation of a push button and returned to its normal inoperative position by 30 its retracting springs.

Another object is to provide means whereby the motor circuit will be automatically closed when the motor is brought to its operative position and the circuit opened when the 35 motor is returned to its normal position.

A further object is to provide the agitator with air jets communicating with the atmosphere to allow the inflow of air into the liquid during the agitation thereof and to 40 cause the streams of air to issue from the jets to be broken up more or less at other points of exit so as to expedite the mixing operation by the agitator.

A still further object is to support the 45 motor and its agitator in such manner that they may be easily and noiselessly moved to and fro and from their mixing position and firmly held against undue vibration when the motor is in action.

50 Other objects and uses relating to specific parts of the apparatus will be brought out in the following description.

In the drawings:

Fig. 1 is a vertical sectional view, partly 55 in elevation of a mixing apparatus embodying the various features of my invention.

Fig. 2 is a plan view partly in section of my invention on line 2—2 of Fig. 1.

Fig. 3 is a sectional view of the agitator.

As illustrated, this apparatus comprises 60 a base —1— having a central platform or rest —2— for receiving and supporting a receptacle as —A— for the liquid to be mixed and is also provided with a pair of vertical sockets —3— at opposite sides of the central platform —2— for receiving the lower ends of a pair of upright standards —4—. These standards are secured in their respective sockets —3— by set screws —5— and extend some distance from the base —1— 70 in parallel spaced relation corresponding to the distance between the sockets —3—, which is sufficient to receive between them the receptacle —A—, said standards being tubular and of substantially the same rectangular 75 cross sectional area from end to end to form substantial guides for an electric motor as —B— which is movable vertically between the standards.

The upper ends of the tubular standards 80 —4— terminate in substantially the same horizontal plane and are provided with removable bushings or plugs —6—, which are held in place by screws —7— and serve to receive anchor bolts —8— for the upper ends 85 of a pair of retracting springs —9—, the lower ends of which are attached to suitable cross heads —10— of the motor frame —B—.

A yoke —11— is provided with caps —12— fitting upon the upper ends of the tubular 90 standards —4— and held in operative position by the screws —7— to brace these portions of the standards against relative lateral movement and to thereby permit the motor to slide freely upon said standards. 95

The cross heads —10— are fitted with an easy sliding fit within their respective tubular standards —4— to slide vertically and are connected by relatively narrow webs —10'— to the main frame of the motor 100 —B—.

The inner sides or walls of the tubular standards or posts —4— are provided with vertical slots —13— to receive the connecting webs —10'— between the motor frame 105 and cross heads —10— and are of sufficient length or height to permit the desired vertical movement of the agitator as —14— into and out of the liquid in the container —A—, said slots being preferably extended to the 110 upper ends of the posts to permit the motor to be placed in operative position and with-

drawn to and from the top of the posts when the plugs —6— and yoke —11— are removed.

The plugs —6— are provided with 5 pendent arms —15— extending downwardly along the inner sides of the posts to form the stops for engaging the upper ends of the cross heads —10— and limiting the upward movement of the motor with the agitator thereon when the various parts are assembled for use.

Suitable means is provided for holding the motor in its extreme down position when the agitator is in operation in the container 15 —A— for mixing purposes and to this end the main body of one of the cross heads —10— is hollow and its outer wall is provided with an aperture —16— near the lower end thereof for receiving a spring 20 catch —17— which is secured to the adjacent wall of the post and is provided with a push button —18— extending through an aperture in the outer wall of the adjacent post —4— for engagement by the finger of 25 the operator to release the catch from interlocking engagement in the aperture —16— and allow the springs —9— to draw the motor and agitator upwardly when the mixing operation is completed.

30 In order that the motor may be normally at rest or disconnected from the motor circuit when in its extreme upward position and that it may be automatically connected in said circuit for revolving the agitator 35 —14— when adjusted downwardly for mixing purposes, I have provided the inner walls of the cross heads with contact terminals —19— which are electrically connected by wires —20— to the motor and are 40 adapted to be moved into contact with spring terminals —21— within the lower portions of the posts —4—, as shown more clearly in Fig. 1, the terminals —21— being electrically connected by wires —22— to a 45 suitable plug, not shown, but which may be inserted in an ordinary electric lamp socket for supplying the necessary current to the motor.

The terminals —19— are mounted upon 50 insulating blocks —23— on the inner walls of the cross heads —10— to insulate the said terminals from the other metal parts.

In like manner the terminals —21— are mounted upon insulating blocks —24— 55 which are secured to the lower portions of the outer walls of the posts —4— by the same screws —5— which fasten the posts to the base —1—. The terminals —21— and terminals —19— are normally separated 60 vertically when the motor is in its extreme upward position but are adapted to be brought into contact with each other when the motor is drawn downwardly by means of a handle —b— on the motor frame.

65 The motor —B— is supported endwise

vertically midway between the standards —4— with its motor shaft as —b'— extending downwardly from the underside thereof, parallel with the standards —4— and its handle —b— disposed substantially 70 midway between the ends of the motor frame at one or both sides thereof to permit it to be conveniently lowered against the action of the retraction springs —9—.

The agitator —14— comprises an upright 75 tube —25— having its upper end embracing and secured by a set screw —26— to the lower end of the motor shaft —b'— while its lower end is preferably closed. Relative small branch tubes —27— are secured to and 80 communicate with the interior of said tube near the lower end thereof and are open at their outer ends to allow atmospheric air, which enters suitable openings —28— in and near the upper end of the tube to pass downwardly through the tube and outwardly 85 through the branch tubes —27—.

A pair of radial projecting U-shaped branches —29— are also secured to opposite sides of the tube —25— to overhanging 90 outer ends of the branch tubes —27— and thereby forming baffles to deflect the air passing out through the branch tubes —27—. The outer portions of the U-shaped tubes —29— may also be provided with apertures 95 —30— for the exit of air to cooperate with the air delivery tubes —27— in causing greater agitation and consequently more rapid mixing of the liquid when the agitator is rotated therein, it being understood that 100 under such conditions the air is thrown by centrifugal force through the branch passages —27— and —30— and assists the agitation caused by the revolution of the branches in the liquid.

105 For a similar purpose the intermediate portion of the tube is provided with downwardly and outwardly deflected branch air tubes —27'— and —29'— similar to the branches —27— and —29— and for the 110 same purpose except that they tend to deflect the air downwardly and outwardly and to increase the agitation caused by the revolution of the branches in the liquid, the outer ends of the branches —29'— being provided 115 with apertures —30'— corresponding to the apertures —30— and the branches —29—.

In operation the motor with the agitator —14— thereon is normally elevated by the springs —9— to its normal or inactive position but may be drawn downwardly 120 through the medium of a handle —b— until the agitators are both in the liquid within the receptacle —A— at which time the motor circuit will be closed by contact of the 125 terminals —19— with the terminals —21—, thus causing the rotation of the motor shaft and agitator while at the same time the motor is locked in its down position by means of the catch —17—. When the mixing oper- 130

ation is completed, the catch —17— may be tripped by pressing inwardly on the button —18— thereby allowing the springs —9— to return the motor and its agitator upwardly 5 to the normal inactive position.

In case it should become necessary to move the motor for repairs or for any other purpose, the yoke —11— would be removed from the upper ends of the posts —4— by 10 removing the locking screws —7—, thus permitting the motor to be lifted vertically until withdrawn from the upper ends of the posts.

It will also be observed that the posts may 15 be readily removed from the base —1— by simply removing the screws —5— and withdrawing the posts upwardly from the sockets —3— which also permits the removal of the insulator sections —24— with the terminals —21— thereon, all of which enables 20 the various parts of the entire apparatus to be easily and quickly assembled or taken apart when desired.

The liquid containing receptacle —A— 25 may be yieldingly held coaxially with the

agitator —14— by means of spring clips —31— mounted in any suitable manner upon the base —1— so as to permit the receptacle to be inserted between them or withdrawn at will.

30

What I claim is:—

An agitator for liquid mixing apparatus comprising a tube having an air inlet near one end and its opposite end closed, branch tubes secured to the main tube and communicating with the interior thereof and having their outer ends open, and additional branches secured to the main tube and overhanging the outer ends of the first named branch tubes in slightly spaced relation 40 thereto to deflect the air escaping from the branch tubes, and means for rotating the agitator.

35

In witness whereof I have hereunto set my hand this 21st day of January, 1920.

WILLIAM M. CALKINS.
